COAT AND SHIRT DISPLAY FORM

Bernard Oestricher, Long Beach, N. Y.

Application July 17, 1940, Serial No. 345,925

6 Claims. (Cl. 223—68)

This invention relates to new and useful improvements in a coat and suit display form.

The invention proposes a display form as mentioned which is characterized by a hollow form body simulating the torso and having a front portion with a flat downwardly inclined neck area at the neck portion, and a recessed area at the front extending from the neck and shoulder to the waist, and a back portion hingedly connected with the front portion at the back of the shoulders. The invention contemplates the provision of means for releasably holding a folded shirt in said recessed front and on said inclined neck area.

Furthermore, means is proposed for holding the front and back portions at various hinged positions.

Another object of the invention resides in an arrangement whereby the bottom portion of the folded shirt may be drawn taut as desired.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a coat and shirt display form constructed in accordance with this invention.

Fig. 2 is a transverse vertical sectional view of Fig. 1.

Fig. 3 is a front elevational view of Fig. 1 but illustrated with the shirt and neck portion removed.

Fig. 4 is a plan view of Fig. 3.

Fig. 5 is a fragmentary enlarged perspective view of the means for holding the front and back portions at various hinged positions.

Fig. 6 is a fragmentary elevational view looking in the direction of the line 6—6 of Fig. 2.

Fig. 7 is a perspective view of the neck member of the device illustrated up side down to disclose the bottom construction.

Fig. 8 is a fragmentary perspective view of the form looking from the rear and above.

Fig. 9 is a perspective view of a coat and shirt display form constructed in accordance with another form of the invention.

Fig. 10 is a vertical sectional view taken on the line 10—10 of Fig. 9.

Fig. 11 is a horizontal sectional view taken on the line 11—11 of Fig. 9.

Fig. 12 is a fragmentary sectional view taken on the line 12—12 of Fig. 11.

Fig. 13 is a fragmentary vertical sectional view taken on the line 13—13 of Fig. 9.

Fig. 14 is a perspective view of a coat and shirt display form constructed in accordance with another form of this invention.

Fig. 15 is a fragmentary horizontal sectional view taken on the line 15—15 of Fig. 14.

Fig. 16 is a fragmentary sectional view similar to Fig. 15 but illustrating a modified construction.

Fig. 17 is another fragmentary sectional view similar to Fig. 15 but illustrating a still further modification of the invention.

The coat and shirt display form, according to this invention, includes a hollow form body 10 simulating the torso and having a front portion 10^a with a flat downwardly inclined neck area 10^b at the neck portion and a recessed area 10^c at the front extending from the neck and shoulders to the waist. The form 10 also includes a back portion 10^d which is hingedly connected with the front portion at the back of the shoulders by a flexible strip 11 secured between the adjacent contacting edges (see Fig. 2).

A folded shirt 12 is rested upon and within the recessed area 10^c. Means is provided for releasably holding the folded shirt 12 in position. This means includes an elastic band 13 extended across the bottom of the recessed area 10^c and attached at its ends upon the material of the form. Additional elastic bands 14 are extended across the upper corners of the recess 10^c and engage over portions of the folded shirt 12 and are attached at their ends upon the material of the form.

A bracket 15 is mounted upon the neck portion 10^b of the form and cooperates to hold the neck band of the folded shirt 12. More specifically, the bracket 15 comprises a stationary portion 15^a secured by fastening elements upon the flat neck portion 10^b and a portion 15^b which is hingedly connected with the portion 15^a and which extends upwards and engages into the collar 12^a of the folded shirt 12 (see Fig. 2). The hinged portion 15^b is provided with a clip 15^c mounted upon the back thereof and adapted to clamp a portion of the collar 12^a against the hinged portion 15^a.

A neck block 16 is adapted to engage within the collar 12^a and at its bottom central portion is provided with a small projecting peg 17. The peg 17 is normally threadedly engaged in a tubular socket 17^a coaxially mounted in the form. 55 This peg 17 must be removed when the neck

block 16 is placed into the collar 12^a of the folded shirt 12. However, when it is desired to place the neck block 16 upon the form without a shirt being displayed, the peg 17 is threadedly engaged into the socket 17^a and the block 16 is placed on the neck portion 10^b of the form in a manner so that the peg 17 extends downwards into an opening 18 formed in the neck portion 10^b of the form. The opening 18 is extended into a reinforcement block 19 mounted upon the bottom face of the neck portion 10^b of the form. The block 16 is also provided with a radially extending groove 20 on its bottom face adapted to accommodate the stationary portion 15^a of the bracket 15. This stationary portion 15^a projects a portion of the shirt upwards into the groove 20. The construction is such that the neck block 16 maintains its position within the collar 12^a of the shirt 12.

Means is provided for holding said front and back portions 10^a and 10^d in various hinged positions. This means includes a pair of arms 21 pivotally mounted at their bottom ends on brackets 22 which are mounted on partitions 23 mounted within the hollows of the form portions 10^a and 10^d. The arms 21 extend upwards and pivotally connect with a bracket 23' which is fixedly mounted on a rod 24 which extends downwards and slidably engages a tubular socket 25. The tubular socket 25 is supported on a bracket 26 which supports a pair of upwardly directed arms 27. These arms 27 are pivotally mounted at their bottom ends on the bracket 26.

The arms 27 are pivotally mounted at their top ends to intermediate portions of the arms 21. The bracket 26 is supported on a rod 28 in end alignment with the rod 24 and which supports a bottom bracket 29. The bottom bracket 29 has a lug 29^a through which a rod 30 slidably passes. A wing screw 31 holds the rod 30 in various positions relative to the bottom bracket 29. The rod 30 extends upwards and at its top end is fixedly connected with a projecting lug 23^a formed in the bracket 23'.

The display form may be supported on the conventional display stand having a vertical rod which may engage into the bottom of the bracket 29 which may then be clamped therein by the wing screw 32. The wing screw 31 may be loosened and the rod 30 may be forced upwards or downwards to move the brackets 23' and 26 and the rods 24 and 28 together or apart. This indirectly causes the arms 21 to spread outwards or move inwards and so the form portions 10^a and 10^d may be placed in various adjusted positions. In this way the form portions may be made to accommodate jackets or coats of various sizes. When a jacket or coat is engaged on the form it conceals the body of the form and only certain portions of the shirt 12 are exposed. The appearance is such that one believes that the shirt 12 is open and engaged on the form. There is no indication that the shirt 12 is in its normally folded position, as sold by the stores.

The form portion 10^a at the top is formed with a recess 33 (see particularly Fig. 8) into which the hinged section 15^b of the bracket 15 may be engaged, as indicated by the dot and dash lines 15', when the form is not being used.

In Figs. 9-13 inclusive a modified form of the invention is disclosed which is very similar to the prior form distinguishing merely in the fact that the form body portion 10^a is provided with a slot 35 formed in the bottom of the recessed area 10^c. The bottom portion 12^c of the shirt is adapted to

be engaged through the slot 35 into the interior form. A rod 36 is pushed through the bottom folded area of the folded shirt 12 so that there are extending end portions 36^a.

5 The end portions 36^a are slipped into the head portions 37^a of bars 37. The bars 37 are slidably engaged in sockets 38 of brackets 39. Set screws 40 hold the bars 37 in various adjusted positions. The brackets 39 are slidably engaged on a bar 40 which is fixedly mounted through one of the arms 21, namely the rear-most arm 21. Set screws 41 hold the brackets 39 in various laterally adjusted positions. The form portion 10^d is provided with a back opening 10^e which is normally closed by a removable section 10^f removably held by several fastening elements 42.

It is necessary that the section 10^f be removed so that access may be had to the bars 36 and 37. In other respects this form of the invention is similar to the previous form and like parts are identified by like reference numerals.

This display form is used substantially the same as the prior form except that the folded shirt 12 may be tautly held down by the rod 36. The slot 35 in the bottom of the recess 10^c is large enough to permit the rod 36 to be passed through when the bottom portion of the shirt is engaged through said opening 35. Then the bars 37 are slipped upon the ends of the rod 36.

When the means for holding the front and back portions 10^a and 10^d is manipulated to spread the portions of the form body, the arms 21 will move, thus moving the bar 40 which indirectly moves the rod 36 pulling taut the shirt 12. It is advisable that the parts be so positioned that the rear arm 21 moves rearwards during the adjustment of the portions 10^a and 10^d of the form. This will pull the bottom portion of the folded shirt 12 rearwards.

In Figs. 14 and 15 another embodiment of the invention has been disclosed which is similar to the prior form, distinguishing merely in the means for releasably holding the folded shirt in position on the form. In accordance with this embodiment, a strip of binding material 50 is mounted upon the front of the form so that there are opposed side portions 50^a of binding material, and a bottom portion 50^b. The edges of the folded shirt are engaged within this binding material which serves to support the shirt in position in conjunction with the support mechanism of the neck portion of the shirt. In other respects this form of the invention is similar to the previous forms.

55 In Fig. 16 another embodiment of the invention is disclosed which is very similar to the form shown in Figs. 14 and 15 distinguishing merely in the fact that binding material 50' has been used which has a plurality of downwardly stamped lug portions 50^c which resiliently grip the edge portions of the folded shirt.

In Fig. 17 another embodiment of the invention is shown in which binding material 50'' has been used, which is substantially of Z-shape in transverse cross section. Fastening elements 52 secure one of the arms of the binding strips 50'' to the material of the form. The other of the arms engages over the edges of the folded shirt. The folded shirt 12 is placed upon a backing member 53 which is adapted to hold the shirt forwards against the front arms of the binding strip 50''.

While I have illustrated and described the preferred embodiments of my invention, it is to be

understood that I do not limit myself to the precise constructions herein disclosed and the right is reserved to all changes and modifications coming within the scope of the invention as defined in the appended claims.

Having thus described my invention, what I claim as new, and desire to secure by United States Letter Patent is:

1. In a coat and shirt display form, a hollow form body simulating the torso and having a front portion with a flat downwardly inclined neck area at the neck portion and a recessed area at the front extending from the neck and shoulders to the waist, means for releasably holding a folded shirt in said recessed front and on said inclined neck area, said front portion having a slot through the material thereof at the bottom of said recessed area for the bottom portion of the folded shirt to pass through, and means for tensioning said bottom portion of said shirt, comprising a rod mounted upon the bottom portion of said folded shirt, and means for holding said rod in various positions to tension said bottom portion of the shirt.

2. In a coat and shirt display form, a hollow form body simulating the torso and having a front portion and a back portion hingedly connected with the front portion at the shoulders, and means for holding said front and back portions in various hinged positions, comprising a fixed rod having a bracket at its top end in turn supporting a tubular socket, a pair of upwardly converging arms pivotally mounted upon platforms mounted within the front and back portions of the form body, a second rod in alignment with said rod and having its bottom end slidably extended into the top of said tubular socket, a second bracket fixedly mounted on the top end of said second rod and having the top ends of said arms pivotally attached thereto, a pair of upwardly diverging arms having bottom ends pivotally attached to said first bracket and their top ends pivotally attached to an intermediate area of said first arms, and means for holding said brackets in spaced positions relative to each other.

3. In a coat and shirt display form, a hollow form body simulating the torso and having a front portion and a back portion hingedly connected with the front portion at the shoulders, and means for holding said front and back portions in various hinged positions, comprising a fixed rod having a bracket at its top end in turn supporting a tubular socket, a pair of upwardly converging arms pivotally mounted upon platforms mounted within the front and back portions of the form body, a second rod in alignment with said rod and having its bottom end slidably extended into the top of said tubular socket, a second bracket fixedly mounted on the top end of said second rod and having the top ends of said arms pivotally attached thereto, a pair of upwardly diverging arms having bottom ends pivotally attached to said first bracket and their top ends pivotally attached to an intermediate area of said first arms, and means for holding said brackets in spaced positions relative to each other, comprising a rod having its top end fixedly attached to said second bracket and its intermediate area slidably extended through an opening formed in said first bracket, and means on said first bracket for holding said latter rod in various fixed positions relative thereto.

4. In a coat and shirt display form, a hollow

form body simulating the torso and having a front portion and a back portion hingedly connected with the front portion at the shoulders, and means for holding said front and back portions in various hinged positions, comprising a fixed rod having a bracket at its top end in turn supporting a tubular socket, a pair of upwardly converging arms pivotally mounted upon platforms mounted within the front and back portions of the form body, a second rod in alignment with said rod and having its bottom end slidably extended into the top of said tubular socket, a second bracket fixedly mounted on the top end of said second rod and having the top ends of said arms pivotally attached thereto, a pair of upwardly diverging arms having bottom ends pivotally attached to said first bracket and their top ends pivotally attached to an intermediate area of said first arms, and means for holding said brackets in spaced positions relative to each other, comprising a rod having its top end fixedly attached to said second bracket and its intermediate area slidably extended through an opening formed in said first bracket, and means on said first bracket for holding said latter rod in various fixed positions relative thereto, comprising a wing screw threadedly engaged through the side of said first bracket and abutting the side of said rod.

5. In a coat and shirt display form, a hollow form body simulating the torso and having a front portion and a back portion hingedly connected with the front portion at the shoulders, and means for holding said front and back portions in various hinged positions, comprising a fixed rod having a bracket at its top end in turn supporting a tubular socket, a pair of upwardly converging arms pivotally mounted upon platforms mounted within the front and back portions of the form body, a second rod in alignment with said rod and having its bottom end slidably extended into the top of said tubular socket, a second bracket fixedly mounted on the top end of said second rod and having the top ends of said arms pivotally attached thereto, a pair of upwardly diverging arms having bottom ends pivotally attached to said first bracket and their top ends pivotally attached to an intermediate area of said first arms, and means for holding said brackets in spaced positions relative to each other, said upwardly converging arms having their bottom ends pivotally attached to brackets mounted on the top faces of the platforms.

6. A coat and shirt display form, comprising a hollow form body simulating the torso and having a front portion with a flat downwardly inclined neck area at the neck portion and a recessed area at the front extending from the neck and shoulders to the waist and a back portion hingedly connected with the front portion at the back of the shoulders, means for releasably holding a folded shirt in said recessed front and on said inclined neck area, means for holding said front and back portion in various spaced hinged positions, said front portion having a slot through which the bottom of said folded shirt extends to the interior of said body, a rod mounted on the bottom portion of said shirt within said body, and means connecting said rod to said back portion to move with said back portion relative to said front portion as said portions are spaced to pull and tension said folded shirt on said front portion.

BERNARD OESTRICKER.
